(57) **CLAIM**

I claim the ornamental design for a dog computer system, as shown and described.

DESCRIPTION

FIG. 1 is a left oblique perspective view of a dog computer system of my new design including respective monitor, keyboard, pointer, and chassis units thereof, the keys of the keyboard unit being shown in dotted, broken lines, forming no part of the claimed design;

FIG. 2 is a front view of the monitor unit;

FIG. 3 is a left side view of the monitor unit, the right side being a mirror image;

FIG. 4 is a top view of the monitor unit, the bottom and rear of the monitor unit forming no part of the claimed design;

FIG. 5 is a right side view of the chassis unit, the left side being a mirror image;

FIG. 6 is a top view of the chassis unit, the rear and bottom sides forming no part of the claimed design;

FIG. 7 is a left end view of the keyboard unit, the key region thereof forming no part of the claimed design; and,

FIG. 8 is a right side view of the pointer unit, the bottom of the pointer unit forming no part of the claimed design.

The elements are shown separately in FIGS. 2-8 for ease of illustration only.
